ware

Application January 4, 1935, Serial No. 340
In Great Britain January 18, 1934

2 Claims. (Cl. 139—16)

This invention relates to improvements in the shedding mechanism of circular looms.

U. S. Patent No. 1,822,292 describes a circular loom in which the shedding is effected by means of a reed having eyed dents through which eyes some of the warp ends are threaded, the remaining warp ends passing between the dents. Above the level of the reed and slightly in advance of each shuttle are placed shedding wheels projecting beyond the line of the warps proceeding to the reed, the shedding wheels being arranged alternately inside and outside the warp circle so that just in advance of each shuttle the warps are deflected either inwards or outwards. Those warps which pass through the eyes of the reed dents retain their normal path below the shuttle, while those warps which pass between the dents are enabled to move either inwards or outwards with respect to the other warps. In this way a shedding movement is initiated, so that the shuttle nose can pass between the two sheets into which the warps have been separated at the rear of each shuttle. The warps return to their normal line and are again shedded by the next shedding wheel in readiness for the entry of the succeeding shuttle.

For easy passage of the shuttles between the warp sheets, this arrangement necessitates alternate shuttles being of somewhat different shape, those shuttles passing into a shed produced by deflecting some of the warps outwards being inclined outwardly with respect to the normal line of the warps and the remaining shuttles inwardly. In addition, the deflection imposed upon the warps, and particularly those restrained by passage through the reed dents, tends to damage the warps. The present invention has for its object to overcome these difficulties.

According to the invention shedding is effected by movable warp-thread controlling healds, through the eyes of which the warp threads are passed, and a member having a surface which presses each heald in turn to propel the healds lengthwise so that the warp threads controlled thereby are moved out of their normal line, there being substantially no relative motion between the pressing surface and the healds at the points of engagement of the healds with the pressing surface.

A shedding wheel between which and the healds there is relative circular motion about the loom axis may be provided to operate the healds, the wheel being disposed so as to press with its edge against an end of the healds and to be rotated thereby by reason of the relative motion, the ro-

tation of the wheel bringing its edge against the end of each heald in turn to propel the healds. The substantial absence of relative motion between the ends of the healds and the edge of the wheel in engagement therewith reduces considerably tendency for sideways thrusting of the ends of the healds by the edge of the wheel as the ends of the healds contact therewith. 5

Conveniently, the healds are arranged in banks around the loom, shedding wheels being provided for each bank. In a loom employing a plurality of shuttles, shedding means are disposed around the loom in accordance with the number of shuttles. Thus, the healds may be arranged in two banks and may be disposed radially around 15 the loom, a shedding wheel arranged inside the warp circle engaging the ends of one bank of healds to deflect those healds outwardly, while a similar shedding wheel arranged outside the warp circle engages the ends of the other bank of healds 20 and deflects those healds inwardly. With this arrangement shedding can take place in a precisely similar manner at each shuttle so that all the shuttles may be identical in shape. Since the shed is formed by both the inside and the outside 25 sheets of warps being displaced from the normal line of the warps, the warps are subjected to little strain.

It is not necessary for the movement applied by the shedding wheels to the healds to be sufficient to separate the warps into the fullest width of shed, since if the warps are separated to such an extent that the shuttle nose can enter, the shuttle will complete the shedding operation as it passes through the warps. In fact, it is desirable that the shedding wheels impart only a small amount of motion to the healds so as to reduce still further the tendency for sideways thrusting of the ends of the healds as they come into engagement with the wheels. 30 35

An important feature of the invention consists in additional means to avoid excessive side thrust. Such means consist of flexible bands, e. g. of spring steel, running round the heald banks, each in contact with the inner and outer ends respectively of the healds of one bank, these bands being conveniently carried by grooves in the peripheries of the shedding wheels. Due to the interposition of the bands between the healds and the edges of the shedding wheels, radial movement 45 of the healds actually commences before the healds have reached the shedding wheels, any tendency of the wheels to push the healds sideways being avoided since there is no direct contact between the wheels and the healds. 50 55

A form of apparatus according to the invention will now be described in greater detail with reference to the accompanying drawing, in which

5 Figure 1 is a fragmentary plan view of part of a circular loom of the type described in U. S. Patent No. 1,822,292, incorporating apparatus according to the invention;

10 Figure 2 is a part cross-sectional elevation viewed along line 2—2 of Figure 1; while

15 Figure 3 is a part cross-sectional elevation viewed along line 3—3 of Figure 1.

As shown in Figures 1 and 2, warp threads unwinding from a beam or other source of supply (not shown) and passing downwardly through 15 a reed 4 to the fabric 5, are shedded into two sheets 6, 7 at intervals around the loom for the reception of shuttles 8 which rest on the fell 9 of the fabric. For further particulars of the shuttles and the method of their operation reference may be had to U. S. application S. No. 20 706,322 filed 12th January, 1934.

The warp threads are shedded into the sheets 6, 7 by radially-disposed blade-like healds 10 which are arranged around the loom above the 25 reed 4 in two banks A, B, the bank A being at a higher level than the bank B. The healds of the lower bank B are supported by the inner and outer rings 11 of the reed 4 (see Figures 2 and 3). The reed contains radial dents 12 extending between the rings 11, the dents being spaced from each other by members 13 which project upwardly and support two pairs of rings 14, 15 which encircle the loom and spring into notches formed in the sides of the members 13. The rings 14 30 are held just above the level of the upper edge of the healds of the bank B, and support the healds of the upper bank A. The rings 15 are held just above the level of the upper edge of the healds of the bank A. In this manner the 40 healds 10 of both banks A and B are free to move longitudinally but are prevented from moving laterally by the members 13, and upwardly by the rings 14, 15.

Each heald 10 is formed with a central eye 16 45 through which a warp end is threaded. For simplicity of illustration alternate warp threads are shown as passing through the eyes of the healds in the same bank, the threads 6 passing through the eyes of the healds in bank B and the threads 7 50 passing through the eyes of the healds in bank A, this being the setting for the production of a plain-weave fabric, as will be apparent from the following description.

As shown clearly in the drawing, shedding of 55 the warp threads into the sheets 6, 7 is effected by longitudinal displacement of the healds of the banks A, B in different directions, this occurring immediately in front of each shuttle 8 progressively round the loom.

60 In order to effect heald displacement, there are provided in association with each shuttle 8 a pair of shedding wheels 17, 18, each of which bears against the ends of the healds 10 of a different bank and pushes the healds towards or away from 65 the axis of the loom. Figure 1 shows two pairs of such wheels, the pair 17, 18 being in association with the shuttle 8 while a similar pair, referred to for convenience as 19, 20, are in association with the following shuttle, which is referred 70 to as 8a.

The wheel 17 is disposed inside the warp circle in line with the healds of the lower bank B, while the wheel 18 is disposed outside the warp circle in line with the healds of the upper bank A and in 75 the same radial line as the wheel 17. Both wheels

17, 18 are positioned so as to protrude beyond the normal line of the ends of the healds 10 in the unshedded position of the warp threads 6, 7.

Relative rotation about the loom axis between the shedding wheels and the heald banks A, B 5 causes the shedding wheels 17, 18 to rotate and to bear progressively against the ends of the healds in the two banks, the healds of the bank A being pushed inwardly, while the healds of the bank B are pushed outwardly, thereby initiating a 10 shedding of the warps as shown in Figure 3. The shuttle 8 then enters between the divided warp sheets 6, 7 and pushes them apart to the desired width. Since the shedding wheels 17, 18 rotate while pressing the ends of the healds, there is 15 substantially no relative motion between the ends of the healds and the edges of the wheels in engagement therewith. In this manner the tendency for sideways thrusting of the ends of the healds by the edges of the shedding wheels is considerably reduced. The warp sheets 6, 7 pass along the sides of the shuttle 8 and on reaching the rear thereof tend to regain their normal unshedded position.

In order to change-over the warp sheets 6, 7 at 25 the rear of the shuttle 8 in preparation for the reception of the next shuttle 8a, the shedding wheels 19, 20 bear against the heald banks A and B, respectively. The healds in the bank A are thus pushed outwardly while the healds in 30 the bank B are pushed inwardly, both moving in the opposite direction to that of their movement under the influence of the shedding wheels 17, 18.

A fresh warp shed is thus started for the reception of the shuttle 8a, as shown clearly in 35 Figure 1. A similar change-over of the warp sheets 6, 7 occurs in front of each shuttle progressively round the loom, the shedding wheels of each pair always bearing against the healds of different banks.

40 In order to reduce still further the tendency for side thrust on the ends of the healds 10 by the shedding wheels 17 . . . 20, endless flexible bands 21, e. g. of spring steel or like material, are provided and fit around the heald banks A, B in 45 contact with the inside and outside ends of the healds. The bands 21 are carried by grooves 22 formed in the peripheries of the shedding wheels and prevent the shedding wheels coming into direct contact with the ends of the healds 10. 50 Any tendency for the shedding wheels to push the ends of the healds 10 sideways is thus avoided, and because of the interposition of the bands between the ends of the healds and the shedding wheels radial movement of the healds actually 55 commences before the healds reach the shedding wheels, this effect being shown clearly in Figure 1.

With two banks of healds A and B, alternate shedding wheels of the inner series, (represented by the wheels 17, 19), carry the flexible 60 band 21 engaging the inner ends of the healds of one bank, and alternate wheels of the outer series, (represented by the wheels 18, 20), carry the flexible band 21 engaging the outer ends of the healds of that bank. The remaining inner 65 and outer shedding wheels carry the flexible bands 21 engaging the inner and outer ends of the other bank of healds.

The inside shedding wheels 17, 19 are supported for free rotation by arms 23 which are 70 adjustably secured in a ring 24 forming part of a spider 25 outstanding from the central shaft 26 of the loom. The outside shedding wheels 18, 20 are similarly supported by arms 27, which are attached to a convenient part of the loom frame 75

(not shown). The adjustability of the arms 23, 27 enables the depth of penetration of the shedding wheels 17 . . 20 into the heald banks, and consequently the initial opening of the warp sheds to be regulated.

In a circular loom in which the warps 6, 7 are stationary while the shuttles 8 rotate, the reed 4 and heald banks A, B are stationary and the shedding wheels 17 . . 20 rotate with the shuttles 10 so as to effect progressive shedding. In this case the outside wheels 18, 20 are secured to a part of the loom frame which rotates at the same rate as the spider 25.

While the invention has been described more particularly with reference to a loom having two banks of healds, it is to be understood that a greater number of heald banks may be incorporated, the shedding wheels being appropriately arranged in accordance with the patterns to be woven. For example, five banks of healds may be used for weaving 5-shaft satin, there being at each shuttle four wheels propelling the healds of four banks in one direction and one wheel propelling the healds of the remaining bank in the other direction. Thus, at each shuttle one warp in every five is separated from the remainder, the first warps being separated at one shuttle, the fourth warps at the second, the second warps at the third, the fifth warps at the fourth, the third warps at the fifth, and again the first warps, and so on.

What we claim and desire to secure by Letters Patent is:—

1. Circular loom shedding mechanism, comprising banks of closely-spaced, individually movable warp thread controlling healds, means for freely mounting and supporting said banks of healds with the healds disposed radially with

respect to the loom axis, endless flexible bands contacting with the healds in each bank, and rotatable shedding wheels between which and said banks there is relative circular motion about the loom axis, said wheels being disposed inside and outside the warp circle so as to press with their edges through said bands against healds in different selected banks to propel the healds of different banks lengthwise in opposite directions and to be rotated by said healds by reason of said relative motion, the rotation of the wheels causing their edges to roll against the bands and to propel each heald in turn in each selected bank so that the warp threads controlled thereby are moved out of their normal line. 15

2. Circular loom shedding mechanism, comprising banks of closely-spaced, individually movable warp thread controlling healds, means for freely mounting and supporting said banks of healds with the healds disposed radially with respect to the loom axis, endless flexible metal bands contacting with the healds in each bank, and rotatable shedding wheels between which and said banks there is relative circular motion about the loom axis, said wheels being disposed inside and outside the warp circle so as to press with their edges through said bands against healds in different selected banks to propel the healds of different banks lengthwise in opposite directions and to be rotated by said healds by reason of said relative motion, the rotation of the wheels causing their edges to roll against the bands and to propel each heald in turn in each selected bank so that the warp threads controlled thereby are moved out of their normal line. 20 25 30 35
